HAIR THINNING DEVICE

Ernst Clemens Matthes, Leipzig, Germany

Application June 14, 1932, Serial No. 617,183
In Germany June 18, 1931

4 Claims. (Cl. 30—1)

This invention relates to a hair thinning out device adapted to be used for raveling out work.

Compared with existing devices for raveling or thinning out hair, which comprise scissors having notches in their cutting surfaces, the thinning out device according to the invention permits mechanical and uniform raveling out during combing and can be used satisfactorily even by inexperienced persons who have not been trained in the difficult technic of raveling out which differs from that of hair cutting in so far as the hair has to be uniformly thinned in spots and not to be uniformly shortened by cutting.

By way of example, the invention is illustrated in the accompanying drawings, in which Figure 1 is a vertical section of two superposed cutting plates having a comb like form and being partly provided with recesses; Fig. 2, a similar section as Fig. 1 of a known device without recesses; Fig. 3, an elevation, partly in section, of the raveling out device ready for work; Fig. 4, an enlarged longitudinal section of two superposed teeth of the comb-like plates with recesses; Figs. 5 to 7 are cross sections of the teeth of the superposed cutting plates showing different forms of recesses.

Referring to the drawings, the thinning out device according to the invention has teeth which comprise a stationary cutting plate 1 and a cutting plate 2, moving over plate 1, both plates having a comb-like form and the cutting of the hair for thinning being effected between the teeth of the plates. The cutting edges of the teeth are provided with the recesses 6 and 7, so that only the cutting portions 8, 9 remain on plate 2.

The recesses 6, 7 will accommodate those hairs that are not to be ravelled out while the device is passing through them, and these recesses as well as the portions 8, 9 of the cutting plate 2 are of different size in consecutive teeth to render raveling out as invisible as possible. By staggering the cutting edge portions 8, 9 uniform cutting action is avoided and even less experienced persons can therefore ravel out hair with a device according to the invention in a satisfactory manner.

As shown in Fig. 1, the cutting members of the movable plate 2 are provided at their base where they extend into the bushing 5 with a large recess 6 which automatically prevents the top layer of the hair, the most important element in hairdressing, from being subjected to raveling out operations. The recess 6 could be arranged also in the stationary cutting plate 1, or in both plates 1 and 2, though numerous tests have shown that it suffices to provide for a recess 6 in the movable

plate 2. During practical application of the device to thick hair the former is passed through the latter from below and the plate 1 held so that the top layer will be adjacent to the bushing 5 and thus cannot be ravelled out, owing to the arrangement of a recess 6 on each tooth. When the hair is of medium thickness or quite thin, the operator will hold the comb obliquely to place the top layer of the hair in the zone where it cannot be cut. This latter manipulation is quite in keeping with the customary practice of hair-dressers who always hold the comb in a slanting position when handling thin hair which they press against the back of the comb to form it into a unit. When applying the device according to the invention, hair-dressers need therefore not to change their usual methods of handling combs and will still be absolutely sure of retaining the long covering top hairs.

As Fig. 3 indicates, the plates 1, 2 are moved relatively to one another only to such an extent that their teeth approximately cover each other when in a position of rest. In operative position, on the other hand, the teeth of one plate would cover the openings 4 of the other. Compared with existing devices, the device according to the invention has little stroke and need not to be displaced to the extent of three, four or more teeth at each cutting operation. In order to attain this the openings 4 are smaller than the adjacent teeth, which makes it possible to dispose, for instance, a tooth of the movable plate 2 in a fully covered position behind a member of the stationary plate 1, and have the opening 4 subsequently fully covered by the larger tooth of the movable plate 2. This covering is so amply dimensioned that it amounts at the overlapping edge portions to at least one-tenth of a millimeter, so that these edge portions may serve as cutting edges for cutting off the hairs to be ravelled out.

In Fig. 3, the movable plate 2 is provided with only half as many teeth as the stationary plate 1, so that every other opening 3 will remain opened also during operation. The openings 3 may be arranged in any desired number. The openings 4 are shown to be approximately of equal width up to the top and have parallel edges, as it has been found that this construction is the most practical and cheapest. Other shapes may be used of course, provided they can be closed by a covering tooth of the movable plate 2 in working position.

At the points where the teeth of one plate cover the openings of the other a closed front will be produced which apparently will prevent the hairs

from passing during further motion of the device.

However, numerous experiments have shown that, owing to the complete closing of the openings 4, the hairs cannot move behind the teeth 5 during the return of the movable plate 2, so that this apparent drawback insures increased safety in operation and perfect freedom from pulling.

Furthermore, according to Figs. 4 to 7, the teeth of the movable plate 2 may be provided with the recesses 10 disposed approximately vertically to the direction of motion, as clearly indicated in Fig. 5, since experiments have proved that a smooth release of the hair from the closing teeth of the movable plate 2 and stationary plate 1 will be insured when the recesses 10 are thus disposed. When the device according to the invention is moved through the hair, the recesses 10 if vertically arranged to the direction of motion of the cutting plates will be in a more favorable 20 position relative to the direction of motion of the hair, which will be approximately similar to the one in which the latter will be drawn out of the teeth.

As stated before, the teeth of the plates 1, 2 having the cutting faces 8, 9 are provided with the recesses 7 to protect the hairs pressed into the recesses during operation of the device from being cut off. In order to facilitate withdrawal of these 30 pressed in hairs, the entrance edges of the recesses 10 in Fig. 6 are rounded. Fig. 6 further shows how the recesses 12 vertically disposed to the direction of motion of the plates 1, 2 may be positioned in the stationary plate 1, the recesses shown being only partial unlike the complete recesses 10 in Fig. 5. If the recesses 12 are provided in the stationary plate 1, the recesses 10 in the movable plate 2 may be made smaller to reduce the tooth only slightly in size.

The vertical recesses in the plate 2 may be curved at 11a and 11b, or these curves may be provided on the stationary plate 1, or on both parts 1 and 2.

Fig. 7 shows how in addition to the vertical recesses 10, 12 the recesses 6, 7, which extend parallel to the direction of motion of the device, may be provided. The combination of these recesses facilitates the withdrawal of the hairs which are not to be ravelled out from the closed teeth. Even long covering hairs need no longer to be combed 45 to the side as is now required but may remain where they are during the raveling out process, and the hair-dresser can observe the effect of his work directly.

Fig. 4 shows how the recesses 6, 7 and 10, 12 vertically disposed relative to one another are positioned in the plates 1, 2 so as to always form the same channels. Furthermore, the vertical channels 10 in the movable plate 2 are bent towards the teeth to provide a more favorable angle

for the outlet of the hairs extending obliquely to the scalp and to prevent them from being injured by the edges of the recesses 10, 12. The shape of the bend is immaterial and may be straight or curved. The bend need further to be provided only at the lower edge while the upper edge may continue to extend vertically. The vertical recesses 10 may be more or less slanting, according to the invention. Fig. 4 further illustrates how by a suitable arrangement of the recesses absolute 10 protection of the hairs of the top layer will be positively assured, as in Fig. 1, since all teeth which count in operation are provided with particularly large recesses 6, 10 near the point where they extend into the plates 1, 2, so that the device 15 can be used also for long and heavy covering hair without exposing it to raveling out.

I claim:—

1. A hair thinning device consisting of a clipper and comprising a toothed stationary cutting plate, a toothed cutting plate adapted to move over said first plate and cooperate with the teeth on said stationary plate thru a limited movement, said teeth having recesses extending transversely of the contacting faces of the cutter teeth to produce longitudinally spaced cutting edges and clearance spaces along the teeth.

2. A hair thinning device comprising a pair of cooperating cutting plates, having forwardly projecting teeth, means for reciprocating one plate 30 relative to the other, the teeth have opposed contacting short cutting edges at their forward ends, and clearance recesses extending transversely of the teeth rearwardly of the cutting edges whereby the hair received in the clearance recess will not 35 be severed.

3. A hair thinning device consisting of a clipper and comprising a toothed stationary cutting plate, a toothed cutting plate adapted to move over said first plate and cooperate with the teeth 40 on said stationary plate through a limited movement, said teeth having recesses extending transversely of the contacting faces of the cutter teeth to produce longitudinally spaced cutting edges and clearance spaces along the teeth, said teeth 45 being disposed at different distances from one another.

4. A hair thinning device consisting of a clipper and comprising a toothed stationary cutting plate, a toothed cutting plate adapted to move 50 over said first plate and cooperate with the teeth on said stationary plate through a limited movement, said teeth having recesses extending transversely of the contacting faces of the cutter teeth to produce longitudinally spaced cutting edges 55 and clearance spaces along the teeth, said teeth being rounded at the recessed portions thereof.

ERNST CLEMENS MATTHES.
